UNITED STATES PATENT OFFICE.

JAMES C. FRENCH, OF KENOSHA, WISCONSIN, ASSIGNOR TO FREDERICK C. AUSTIN, OF CHICAGO, ILLINOIS.

MIXING-MACHINE.

1,314,390.

Specification of Letters Patent. Patented Aug. 26, 1919.

Application filed April 5, 1915. Serial No. 19,131.

To all whom it may concern:

Be it known that I, JAMES C. FRENCH, a citizen of the United States of America, and resident of Kenosha, Kenosha county,

5 Wisconsin, have invented a certain new and useful Improvement in Mixing-Machines, of which the following is a specification.

My invention relates to mixing machines of that kind in which the rotary receptacle is provided with an opening for both receiving the materials and discharging the batch after the mixing operation is completed. In 10 a mixing machine of this general character, the said receptacle is usually mounted to be tilted into one position for receiving the materials and for rotation in this position to produce the mixture, and the said receptacle is also capable of tilting movement in the other direction to bring the said opening into position for discharging the batch. 15 Ordinarily, the said receptacle or tub-like container is annular in character, and is arranged to tilt about a horizontal axis which is coincident, or approximately so, with the 20 axis of rotation of the receptacle.

An object of my invention is to provide a mixing machine of this kind in which the said receptacle approximates a cube to a certain extent, or is semi-cubical in form, there- 25 by increasing the efficiency of the machine.

Another object of the invention is to provide an improved construction and arrangement whereby the receptacle tilts about an offset axis to bring the opening thereof into 30 a low position for charging the receptacle, thereby facilitating the introduction of the materials into the receptacle, and into a relatively high position for discharging the batch, as will hereafter more fully appear.

40 It is also an object to provide certain details and features of construction tending to increase the general efficiency and serviceability of a mixing machine of this particular character.

45 To the foregoing and other useful ends my invention consists in matters hereinafter set forth and claimed.

In the accompanying drawings—

Figure 1 is a side elevation of a mixing 50 machine embodying the principles of my invention.

Fig. 2 is a plan of the machine shown in Fig. 1, showing the forward portion thereof broken away for convenience of illustration.

Fig. 3 is an end elevation of the said machine. 55

Fig. 4 is a detail sectional view of the bottom of the receptacle.

Fig. 5 is a bottom plan view of the receptacle. 60

As thus illustrated, my invention comprises a body A, and as the machine is designed for use on the street, and to be moved from place to place, the said body is preferably provided with front and rear wheels 65 a and B of any suitable character. The upright frames C and D are suitably mounted on the said body, and arranged to support between them the swinging frame E, the latter being provided with trunnions e carried at the upper ends of said upright frames. The rotary receptacle F is of any suitable or known shape, cubiform or semi-cubiform, as shown, and is provided in the flat bottom thereof with a fixed cylindric 70 member or stem which extends through the supporting frame E and is provided at its lower end with a reduced portion having a retaining nut G, a ball-bearing g being arranged on top of the frame E to support the 80 said receptacle, and the said member or stem f forming the axis of said bearing, whereby the receptacle is adapted to rotate about a central axis. For this purpose one of the trunnions e is provided with a short shaft 85 H extending centrally thereof, said shaft having a bevel gear h for engaging the bevel gear ring I which is secured to and encircles the said receptacle. A sprocket connection J connects the outer end of this shaft with 90 the engine K, these elements being of any suitable or desired character. The receptacle has a round top opening F² which serves as both a charging opening and a discharge outlet. With this arrangement 95 the said receptacle is driven by the engine during the mixing operation.

In order that the said receptacle or tub-like container F may efficiently mix the materials, the form or construction thereof is 100 as follows: Starting with a cube, three adjacent sides thereof 1, 2 and 3 form the lower sides of the receptacle. The other sides of the tube 4, 5 and 6 are expanded outward slightly and connected by intermediate 105 rounded corners 7, whereby a round opening 8 is formed at the top of the receptacle, the center of said opening being approximately

at one corner of the said imaginary cube. It will also be seen that the said cube is still further distorted by the cutting off of the corner portion which is diametrically opposite the said opening, thereby providing the triangular bottom surface 9 as shown in Fig. 5. In this way, and as stated, three of the sides of the cube, 1, 2 and 3, are left perfectly flat, but are reduced from a perfect square in each case by the formation of the flat surface 9; and the other three surfaces of the said imaginary cube, 4, 5 and 6, are distorted by the outward bulging thereof, which distortion is necessary in order to 10 taper the receptacle into the rim of said opening—that is to say, in order to provide side walls which extend directly to said rim at angles approximating the said three sides of the cube. Thus, as stated, the receptacle 15 is of semi-cubical form, the shape thereof being obtained by the above described distortions of or variations from a perfect cube. When thus constructed, the said receptacle 20 becomes possessed of side surfaces or side walls which, when the receptacle is rotated 25 about the axis 10—10 shown in Fig. 3, serve to toss the materials back and forth within the receptacle, in a manner which will be readily understood, and to a certain extent 30 after the fashion of the ordinary and well known cube mixer, but which latter is usually provided with one opening for charging and another opening for discharging the batch. In other words, and with the foregoing construction, the opening 8 is of the proper size for both receiving and discharging materials, notwithstanding the fact that the shape of the receptacle approximates to a large extent the form of a cube.

As a matter of special improvement, an offset center for tilting the receptacle into receiving position, or into dumping position, is provided as follows: The frame E is deflected to one side at its center, as shown in Fig. 2, so that the axis of rotation of the receptacle is some distance to one side of the horizontal axis provided by the trunnions e, whereby the entire receptacle is lowered to a position shown in full lines in Fig. 3, thus bringing the round opening F into a position for charging the receptacle with materials to be mixed; also, and in this position, the receptacle is rotated to mix the materials. After the mixing operation is completed, the said receptacle is then swung over to the other side of the machine, and into the inverted position shown in dotted lines in Fig. 3, whereby the receptacle is at this time in a higher position than would be the case should the tilting axis be located exactly at the center of the receptacle; and in this way a conveniently low position is insured for the receptacle when it is swung into position to receive the load, and a com-

paratively high position when it is turned over and moved into position for discharging the load.

Any suitable means can be employed for tilting the receptacle. For example, the trunnion at the end of the machine can be provided with a fixed gear wheel L, which is segmental in form and provided with two large teeth l which limit the tilting movement of the receptacle, inasmuch as these teeth cannot pass the pinion M which operates the said gear wheel. A hand wheel m is provided for rotating the pinion M when it is desired to tilt the machine to dumping position, it being understood that the offset arrangement of the tilting axis causes the receptacle to remain of its own weight in charging and rotating position, as shown in full lines in Fig. 3; and in this connection it will be understood that in Figs. 1 and 2 the said gearing is assumed to have been operated to an extent sufficient to bring the receptacle into an upright position with its axis of rotation exactly vertical, whereby the shape of the receptacle is more clearly shown.

The bottom of the said receptacle is provided with an inner extension N which surrounds the pin or axis member f, and which holds the latter very solidly and firmly in place. Thus the pin or cylindric axis member f is made a rigid part of the receptacle itself, but the weight of the receptacle is sustained by the ball-bearing g in the manner previously described. With this construction, the receptacle is rotatable about the axis 10—10 in Fig. 3. From the foregoing it will be seen that a tub mixer is provided having the advantages of the well known cube mixer, as previously explained, so far as the shape of the receptacle is concerned. Also that the tilting of the receptacle is about an offset axis which facilitates the charging of the machine, and which insures a higher and better position for discharging the batch or load. It will also be seen that by reason of this offset tilt, the receptacle is set low on the body of the machine, and that notwithstanding this low position it may swing over and assume a dumping position without coming in contact with the body frame member or reach O which is disposed immediately below; it being observed that when the receptacle is tilted in the opposite direction, and into charging position, the bottom thereof is close to this member O, and that the receptacle cannot swing farther in this direction; but by reason of the offset axis the other side of the receptacle does not strike the member O when the receptacle is tilted in the opposite direction for discharging the load.

With the construction shown and described, the receptacle F has an open top and a closed bottom, so that it has only one open-

ing for either inlet or outlet purposes. Furthermore, the said receptacle is mounted to tilt about a horizontal axis located a distance above the bottom of the receptacle, so that the latter is in low position for loading. Also, this brings the mouth of the receptacle into a suitably elevated position for discharging the batch. By reason of the offset axis—that is to say, the horizontal axis 10 about which the receptacle tilts, the weight of the receptacle tends to make it gravitate in one direction only, when in a horizontal or upright position, as the weight is considerably greater at one side than at the other. In other words, the said horizontal axis of tilting motion is located some distance from the upright axis about which the receptacle rotates, so that the two axes do not intersect each other. Thus, the said 20 horizontal axis of tilting motion is not only some distance above the bottom of the receptacle, as well as some distance below the top of the receptacle, but is also located at some distance from the center of the receptacle, being much nearer one side of the receptacle than the other. With the construction shown and described, it will be seen that the horizontal axis of the bail-shaped frame E and the vertical axis of the receptacle F are not in the same vertical plane, when the receptacle is horizontal, but are in different vertical planes and spaced apart a distance sufficient to unbalance the receptacle, in the manner explained.

35 What I claim as my invention is:—

1. A mixer comprising a rotary receptacle of cube form having one corner thereof cut off to provide a triangular bottom and having the opposite corner cut off and shaped to form a top having a round receiving and discharge opening, so that when viewed from above said receptacle is an equal sided hexagon in outline, and having the axis of rotation thereof extending through the receptacle at the center of said base and at the center of said opening, which axis is vertical when the bottom and top are level.

2. A mixer comprising a receptacle having a closed bottom and a receiving and discharge opening at the top thereof, a support upon which said receptacle is mounted to rotate about an axis extending through said base and opening, which axis is vertical when the open top is level, and means to 55 tilt said support about a horizontally disposed axis at one side of said vertically disposed axis of rotation, said horizontal axis and said vertical axis being in different vertical planes in order that the receptacle 60 when in horizontal position and when its

axis is vertical shall have a tendency to tilt in one direction only, and so that said receptacle will be lowered to receive the charge when tilted in said one direction from its upright position, and will be 65 raised when tilted in the opposite direction to discharge the batch.

3. The structure specified in claim 2, in which said receptacle has a bevel gear ring, a bevel pinion at one end of said support 70 to engage said bevel ring, the axis of said pinion being coincident with the axis about which said receptacle tilts, so that the axis of the ring and the axis of the pinion are in separate vertical planes when the ring 75 is in horizontal position, and means to rotate said pinion to rotate said receptacle.

4. The structure specified in claim 2, in which said support is depressed a distance and also laterally displaced relatively to the 80 axis thereof, so that said support is bail-shaped with its middle at one side of the vertical plane of the horizontal axis when the receptacle is upright, and in which said base of the receptacle has a bearing on said 85 laterally displaced portion of said support, thereby to bring the center of gravity to one side of the axis of said support when said receptacle is in an upright position.

5. In a mixing machine, the combination 90 of trunnion bearings, a bail-shaped member supported by said bearings, a receptacle having an open top and a closed bottom, a bearing on said bail-shaped member for the bottom of said receptacle, so that said receptacle is rotatable about an axis disposed at right angles to the axis of said bail-shaped member, the axis of said receptacle being spaced a distance from the other axis, whereby the receptacle is unbalanced and 100 tends to tilt downward at one side thereof when its axis is vertical, means to rock said bail-shaped member about its axis, thereby to swing the receptacle upward and over from its receiving position to its discharging position, and mechanism for rotating the receptacle on said bail-shaped member. 105

6. A structure as specified in claim 5, said mechanism comprising a shaft extending through one of said trunnion bearings, a 110 bevel pinion on said shaft, and a gear ring encircling said receptacle to engage said pinion.

Signed by me at Chicago, Illinois, this 25th day of March, 1915.
